UNITED STATES PATENT OFFICE.

ISAAC W. CHISHOLM AND CHARLES S. JOHNSON, OF NEW CONCORD, OHIO.

DESIGN FOR A MEDICINE-REGISTER.

SPECIFICATION forming part of Design No. 17,907, dated November 29, 1887.

Application filed April 26, 1884. Serial No. 129,476. Term of patent 3½ years.

To all whom it may concern:

Be it known that we, ISAAC W. CHISHOLM and CHARLES S. JOHNSON, citizens of the United States, residing at New Concord, in the county of Muskingum and State of Ohio, have invented and produced a new and original Design for Medicine-Registers, of which the following is a specification, reference being had to the accompanying drawings, forming part thereof.

Figure 1 is a view illustrating the front of our newly-designed register, and Fig. 2 is a view of the reverse side.

The design consists, essentially, of a disk provided on its front side with a central panel, A, encircled by two or more annular lines, between which are a number of characters. Within the central panel, and toward one side thereof, is the representation of a human figure, one of the shoulders of which occupies a central point within the panel, and is extended

to present an arm, B. The disk is provided at its upper side with a peripheral extension, C, as shown. The reverse side of the disk is simply formed of an annular ring constituting a central panel, D, and marginal space E, in which panel or space may be placed any desirable printed or written matter.

We claim—

A design for medicine-register herein shown and described, the same consisting of a disk provided with a central panel on which is the representation of a human figure having one of its arms directed toward the circumference of the disk, as set forth.

In testimony whereof we affix our signatures in presence of two witnesses.

ISAAC W. CHISHOLM.
CHARLES S. JOHNSON.
